United States Patent Office.

EMORY McCLINTOCK, OF NEW BRUNSWICK, NEW JERSEY.

Letters Patent No. 70,590, dated November 5, 1867.

IMPROVEMENT IN STEAM ENGINES.

The Schedule referred to in these Letters Patent and making part of the same.

TO ALL WHOM IT MAY CONCERN:

Be it known that I, EMORY McCLINTOCK, of New Brunswick, in the county of Middlesex, and State of New Jersey, have invented a new and useful Improvement in Steam and Water Engines and Pumps; and I do hereby declare that the following is a full, clear, and exact description thereof, which will enable others skilled in the art to make and use the same, reference being had to the accompanying drawings, forming a part of this specification.

This invention relates to a new and improved construction and arrangement of the parts of steam and water engines and pumps, whereby the power may be applied to the pistons in the simplest manner; and the invention consists in the combination of the valve-ports and passages in the pistons and cylinders, whereby the pistons act as four-way cocks in each of the cylinders, for the distribution of steam or other fluid or liquid for the other cylinder, as will be hereinafter more fully described.

Figure 1 represents a sectional horizontal plan view of the engine through the line $z z$ of fig. 2, showing two cylinders, with a double-acting piston in each, with connecting-rods attached to a main shaft by cranks.

Figure 2 is a vertical section of fig. 1 through the line $y y$.

Figure 3 is a vertical section through the line $z z$ of fig. 1.

Similar letters of reference indicate corresponding parts.

The peculiarities of this invention are limited to the arrangement of the cylinders and pistons. The guides, governor, and governor-valves, and other details, have been omitted as unnecessary in this description.

The cylinders C and C' are cast together, and lie in a horizontal or other convenient position. The pistons P and P' are represented as cast solid with the piston-rod, but they may be constructed and packed, and connected with the main shaft, in any ordinary manner. There are four valve-ports in each cylinder; one, S , at the lower side of the first cylinder C , and one, S' , at the lower side of the second cylinder C' , both opening from the steam pipe X ; one port, E , in the first cylinder C , and one, E' , in the second cylinder C' , opening into the exhaust pipe Y , directly opposite each other, at an angle of ninety degrees from the steam-ports just mentioned; one port, U' , in the first cylinder C , and one port, L , in the second cylinder C' , in each case midway between the said steam and exhaust-ports, communicating, respectively, the former with the upper or forward end of C' , and the latter with the lower or rear end of C . There are also, at an angle of forty-five degrees above the said exhaust-ports, one port or passage L' , in C , communicating with the lower or rear end of C' , and one, U , in C' , communicating with the upper or forward end of C . Each valve-port is equidistant from the ends of the cylinders. The passages through the first piston P are so made that when it moves from the middle point of the stroke, away from the shaft, and till it returns, there is communication through one passage, a , from the steam pipe S to the passage L' , leading to the lower end of cylinder C' , and through another passage, b , from the passage U' , leading from the upper end of C' to the exhaust-port E , causing, while the said first piston P is performing the second half of the down stroke and the first half of the up stroke, such a circulation of steam to and from the cylinder C' as to produce a complete up stroke of the other piston, P' . The other passages, c and d , are brought into play when the first piston, P , moves from the central position towards the shaft, and until it returns, producing in a similar manner a complete down stroke of the piston P' . The passages a' , b' , c' , and d' in the piston P' are similarly constructed, distributing the steam in proper manner for the first cylinder C , and producing the regular reciprocating motion of the piston P . The starting of the engine is instantly effected upon letting on the steam, as is the case usually with double-cylinder or right-angled engines.

In speaking of the stroke of the engine, I desire it to be understood that I mean the passage of the piston the length of the cylinder, (a double stroke producing a revolution of the crank,) and that in using the word cylinder I do not confine myself to vessels mathematically cylindrical in shape.

I prefer to employ cylinders and pistons similar in size and arrangement, including length of stroke, although such resemblance is not essential.

This invention is applicable to engines operated by other fluids or liquids, and to pumps, and the water engine may be advantageously used as a meter.

No two of the valve-ports should lie in the same axial line, as this would compel an enormous increase in length of cylinder and piston, and in order to save space I prefer to have all the valve-ports in the same

transverse plane. Each piston must be of such length as to keep the valve-ports separated at all points of its stroke from any communication with the chambers of its own cylinder above and below it; and also of such construction that, when at the middle of its stroke, (in point of time,) there shall be no room for the passage of steam through said valve-ports in any direction. This stoppage of the circulation of steam takes place twice in every double stroke of each piston as it passes the said middle point, the other piston being at such time at the end or dead-point of its stroke.

There may be no limit to the number of valve-ports, but all or any of them may be duplicated or multiplied in number when desired, whether to secure a more perfect equilibrium of steam pressure or for other purposes.

The passages in the pistons may be of any desired construction, number, and position, provided they be of such construction, with reference to the valve-ports of the cylinder, that when the piston moves in one direction from the central position, and until it returns to the same position, there shall be communication for the passage of steam between the steam-port or ports and the port or ports communicating with the upper or first chamber of the other cylinder, and also between the port or ports communicating with the lower or second chamber of the other cylinder and the exhaust-port or ports, thus causing the piston of the other cylinder to make a complete stroke; and that when the piston moves in the other direction from the central position, and until it returns to the same position, communications the reverse of the above shall be established, so as to cause the return stroke of the other piston.

A convenient reversing arrangement consists in the addition of a valve or valves, of any usual construction, by which the steam may be made to flow in the opposite direction through the engine. By this means the functions of the steam and exhaust pipes may be interchanged at pleasure. Additional "expansion" or "cut-off" arrangements can easily be applied, when desired, according to any of the systems already in use.

Steam engines of all of the various kinds, as trunk, locomotive, traction, and fire engines, as well as the various models of stationary engines, may be advantageously constructed according to my invention.

Having thus described my invention, what I claim as new, and desire to secure by Letters Patent, is—

The combination of the valve-ports S S', E E', U U', L L', in the cylinders C C', and the passages a b c d and a' b' c' d' in the double-acting pistons P P', said pistons serving as four-way valves, all substantially as herein described, for the purposes specified.

EMORY McCLINTOCK.
